SHOE PRESS

Fred Dawson, West Roxbury, Mass., assignor to
 Compo Shoe Machinery Corporation, Boston,
 Mass., a corporation of Delaware

Application June 2, 1942, Serial No. 445,432

19 Claims. (Cl. 12—33)

This invention relates to presses for use in shoe manufacturing operations and more particularly to a press used for adhesively attaching outsoles to lasted shoe uppers.

A general object of the invention is to provide a sole attaching press into which shoes of varying sizes and shapes may be easily inserted and soles affixed thereto or other pressing operations performed in a rapid and efficient manner.

Another object of the invention is to provide a shoe press unit having a dilatable sole pressing diaphragm and power operated shoe clamping devices to clamp a shoe thereto.

A further object of the invention is to provide a shoe press with opposed dilatable diaphragms for clamping a shoe and pressing a sole thereto, which are dilated from a common fluid pressure source in a desired sequence.

Further objects of the invention are to provide a shoe press unit possessing the above and other advantageous features which is simple and sturdy in construction and in which a shoe may be clamped and a pressing operation performed thereon with a minimum expenditure of time and effort by the operator.

Other objects of the invention will in part be obvious and will in part appear hereinafter.

The invention accordingly comprises the features of construction, combination of elements, and arrangement of parts, which will be exemplified in the construction hereinafter set forth and the scope of invention will be indicated in the claims.

For a fuller understanding of the nature and objects of the invention reference should be had to the following detailed description taken in connection with the accompanying drawings, in which:

Fig. 1 is a plan view of a shoe press embodying features of the present invention;

Fig. 2 is sectional side elevation of the shoe press shown in Fig. 1, taken substantially along lines 2—2 of that figure and shown in its inflated or shoe pressing condition;

Fig. 3 is a sectional side elevation similar to Fig. 2, but showing the press in its deflated condition;

Fig. 4 is a transverse vertical sectional view taken substantially along lines 4—4 of Fig. 3;

Fig. 5 is an end elevation looking in the direction of the arrows 5—5 of Fig. 2, parts being broken away to better illustrate the construction;

Fig. 6 is a transverse vertical sectional view taken substantially along lines 6—6 of Fig. 2; and

Fig. 7 is a plan view looking at the underside of the press.

In the attaching of soles to shoes with an adhesive it is general practice to coat the marginal edge of the prepared shoe bottom and outsole with an adhesive and thereafter apply a solvent or softening agent to the cemented areas and place the parts in proper relation in a shoe press having an inflatable pad with sufficient vertical expansion to clamp the outsole to the shoe and the shoe to fixed abutments above the pad. While this method is fairly satisfactory it requires considerable attention and effort on the part of the operator to hold the shoe in position until the pad expands sufficiently to clamp the shoe against its pressure resisting abutments and of course the pad is subjected to a considerable strain due to its excessive vertical expansion to clamp varying sizes of shoes, resulting in a short and rather indefinite life.

Another commonly used method of adhesively attaching a sole to a shoe utilizes a semi-solid sole pad and pressure is brought to bear upon the last and shoe to press it and the sole to the pad, which necessitates the use of a movable clamping device which has to be brought into shoe clamping position by the operator prior to the application of the sole attaching pressure and thus consumes considerable time and effort.

The present invention clearly simplifies the attaching of a sole to a shoe in that the manual movement of clamping devices is eliminated and the sole pressing pad does not require any great degree of expansibility, thus operating time and effort is greatly reduced and useful life of the sole pressing pad is materially increased.

Referring to the drawings and first to Figs. 1 and 2 there is shown in the dilated or shoe pressing position an inflatable shoe press having a base 10 the central portion of which is cored out at 11 and the upper marginal face 12 preferably on a level plane. In superposition and firmly secured to the upper face 12 by a somewhat oval shaped clamping ring 13 and spaced bolts 14 are a flexible lower or shoe clamp operating diaphragm 15, a rigid pressure resisting dividing plate 16 and an upper or sole pressing diaphragm 17, thus forming two opposed fluid tight chambers 18 and 19 each having a flexible and dilatable diaphragm. The central portion of the dividing plate 16 is preferably contoured to the general shape of a shoe bottom and the sole pressing diaphragm 17 in its normal or non-dilated condition rests thereon and assumes the same general shape (as shown in Figs. 3 and 4), thus afford-

ing easy placement of a shoe in correct position on the diaphragm.

A simple yet effective arrangement for clamping a shoe and positioned outsole on the diaphragm 17 comprises a toe clamping member 20 having a threaded stem 21 which is screwed into a support 22 slidably mounted on ways 33 provided on the clamp arm 24. The toe clamping member being locked in position by the lock nut 25 and the support 22 may be positioned and secured in place with a thumb screw or the like. To allow the toe clamp 20 to be moved towards and away from the diaphragm so as to clamp or release a shoe it is freely pivoted on a shaft 26 held in upstanding lugs 27 extending from the base frame 10. Pivoted at 28 to each side of a boss 29 extending transversely of the clamp arm 24 are depending links 30 which at their lower ends pivot on a shaft 31 held in a boss 32 formed on a pressure platen 33. This pressure platen 33 is freely swingable about a shaft 34 held by lugs 35 depending from the base frame 10 and its forward end is adapted to enter the cored out portion 11 of the base and is held in contact with the lower diaphragm 15 by a torsion spring 36.

A similar arrangement is provided for clamping the heel end of the shoe and comprises a last cone abutting member 40 having a stem 41 screw threaded into a beam 42 secured by screws 43 to a bail 44 which straddles the press and which is pivoted at its lower ends to a shaft 45 held in a boss 46 extending transversely of another pressure platen 47. This pressure platen is freely swingable about a shaft 48 held by lugs 49 depending from the base frame 10 and a torsion spring 50 centered on the shaft 48 gives the platen a bias towards the lower diaphragm 15. To keep the bail 44 in an upright position links 51 are pivoted at 52 to each leg of the bail and at their opposite ends to lugs 53 extending from the base frame 10.

It can readily be understood that as long as the chamber 18 is not inflated, the diaphragm 15 will lie against the underside of the dividing plate 16 and the pressure platens 33 and 47 under their spring bias and by virtue of the connections described will elevate the toe and heel shoe clamping members 20 and 40. However, when the lower chamber 18 is inflated by fluid pressure means hereinafter described the diaphragm 15 will be dilated and will cause a pressure to be exerted on the platens 33 and 47 which have a combined area somewhat greater than the largest shoe bottom causing them to swing downwardly about their pivots and consequently bring the toe and heel clamping members into clamping relation with a shoe placed upon the upper diaphragm 17.

An effective arrangement for inflating the chambers 18 and 19, and dilating the diaphragms in a desired sequence to cause the clamping of a shoe to the upper diaphragm 17 as previously described and to thereafter dilate the upper diaphragm to conform and press the sole to the shoe is best shown in Figs. 2 and 6 and comprises the provision of a boss 60 formed on the under side of the dividing plate 16 and having a bore 61 extending throughout its entire length. A conventional plunger type inflating and deflating valve 62 is screw threaded into the bore 61 where it may be coupled to an air chuck 63 of the type described in the Weiss Patent No. 1,945,762, and a fluid under selected working pressure be introduced via the bore 61 into the lower chamber 18 thus causing the diaphragm 15 to dilate and effect clamping of the shoe. As inflation of the lower chamber is continued and the pressure increases a few pounds

per square inch above atmospheric pressure, communication to the upper chamber 19 is afforded by means of an inflating port 64 formed in the dividing plate 16 and covered on the upper side by a leaf spring valve 65 secured in place by a screw 66. Thus, as inflation is continued to final sole attaching pressure fluid flowing under pressure in to the lower chamber 18 overcomes the slight resistance of the leaf spring valve 65 and is admitted into the upper chamber 19 causing dilation of the sole pressing diaphragm 17 which conforms to the shape of the shoe bottom and presses the sole thereto.

As the pressure is built up in both upper and lower chambers the pressures tend to equalize and the upper diaphragm 17 rises away from the dividing plate 16 carrying with it the shoe pressed against the abutments 20 and 40. This rise of the upper diaphragm continues and the lower diaphragm 15 recedes towards the dividing plate until a state of balance exists i. e., when the press is fully inflated the diaphragms are spaced from the dividing plate 16 an amount approximately in proportion to the ratio of the area of the shoe being processed and the areas of the platens 33 and 47. As previously stated, the combined areas of the platens 33 and 47 are greater than the largest shoe to be processed, thus, the upper diaphragm 17 never dilates or balloons as much as the lower diaphragm insuring contact of the upper diaphragm with the entire area of the shoe sole.

The press is adapted to be used on a machine such as that described in the aforementioned Weiss patent and deflation of the press is accomplished by depression of the plunger 67 of the valve 62 which allows the fluid to escape from, and the pressure in the lower chamber 18 to decrease, and as it decreases the higher pressure in the upper chamber 19 opens the light leaf spring valve 68 secured on the under side of the dividing plate 16 and covering the deflating port 69 thus allowing the fluid to escape from the upper chamber 19 via the lower chamber 18 and the valve 62 until the pressures reach atmospheric. During such deflation, the diaphragms return to their normal position and the toe and heel clamps are elevated away from the shoe allowing it to be easily removed and another inserted by passing it between the bail 44.

It is to be understood that this description is illustrative and that various changes may be made in the structural details and mode of operation without departing from the scope and spirit of the invention. Thus, the upper chamber 19 may be filled with a liquid and the ports 64 and 69 eliminated so that as the lower chamber 18 is inflated the toe and heel clamp will apply pressure and clamp the shoe to the upper diaphragm displacing the liquid and allowing the diaphragm to conform to the shape of the shoe bottom. Also each chamber may be fitted with an inflating and deflating valve 62 and two air chucks employed to inflate the chambers to any desired pressures.

It is also understood that the following claims are intended to cover all of the generic and specific features of the invention herein described, and all statements of the scope of the invention which, as a matter of language, might be said to fall therebetween.

Having thus described my invention, what I claim as new and desire to secure by Letters Patent, is:

1. In a shoe press the combination comprising, two opposed dilatable diaphragms, operator

controlled pressure means for dilating one of said diaphragms, and automatically operated means for thereafter allowing pressure to be applied to the other of said diaphragms to dilate it in an opposite direction.

2. In a shoe press the combination comprising, two opposed dilatable diaphragms, means dependent upon dilation of one of said diaphragms to clamp a shoe to the other of said diaphragms, operator controlled valve means for dilating one of said diaphragms with a fluid, and automatically operated valve means for thereafter dilating the other of said diaphragms with a fluid.

3. In a shoe press the combination comprising, two opposed dilatable diaphragms, means dependent upon dilation of one of said diaphragms to clamp a shoe to the other of said diaphragms, operator controlled valve means for dilating one of said diaphragms with a fluid under pressure, and automatically operated valve means for thereafter dilating the other of said diaphragms with the same fluid.

4. In a shoe press the combination comprising, two opposed dilatable diaphragms, means dependent upon dilation of one of said diaphragms to clamp a shoe to the other of said diaphragms, operator controlled valve means for dilating one of said diaphragms with a fluid under pressure, and valve means automatically operated by said fluid pressure to thereafter allow the other of said diaphragms to be dilated with the same fluid.

5. In a shoe press the combination comprising, a rigid pressure resisting plate, flexible diaphragms secured to each side of said pressure resisting plate so as to form two separate chambers, means for introducing a fluid under pressure into one of said chambers and means for transferring said fluid from one chamber to the other.

6. In a shoe press the combination comprising, a rigid pressure resisting plate, flexible diaphragms secured to each side of said pressure resisting plate so as to form two separate chambers, means for introducing a fluid under pressure into one of said chambers, means for transferring some of said fluid to the other of said chambers and means for exhausting the fluid from both chambers.

7. In a shoe press the combination comprising, a rigid pressure resisting plate, flexible diaphragms secured to each side of said pressure resisting plate so as to form two separate chambers, means for introducing a fluid under pressure into one of said chambers and means acting when a definite pressure is reached to allow fluid to enter the other of said chambers.

8. In a shoe press the combination comprising, a rigid pressure resisting plate, flexible diaphragms secured to each side of said pressure resisting plate so as to form two separate chambers, operator controlled means for inflating one of said chambers to dilate its diaphragm, means operated automatically by said inflation to thereafter allow inflation of the other of said chambers to dilate its diaphragm and means for deflating both of said chambers.

9. In a shoe press the combination comprising, a rigid pressure resisting plate, flexible diaphragms secured to each side of said pressure resisting plate so as to form separate upper and lower chambers, operator controlled means for introducing a fluid under pressure into said lower chamber to cause dilation of its diaphragm, valve means associated with said pressure resisting

plate to allow fluid to pass from said lower chamber to said upper chamber to dilate its diaphragm, and means for relieving the fluid pressure from both of said chambers.

5 10. In a shoe press the combination comprising, a dilatable sole pressing diaphragm and a dilatable clamp operating diaphragm, shoe clamping means disposed over said sole pressing diaphragm and movable to clamp a shoe

10 thereto by dilation of said clamp operating diaphragm, means for dilating said clamp operating diaphragm and means for thereafter dilating said sole pressing diaphragm to press an outsole against the shoe clamped to it.

15 11. In a shoe press the combination comprising, a dilatable sole pressing diaphragm and a dilatable clamp operating diaphragm, shoe clamping means disposed over said sole pressing diaphragm and movable to clamp a shoe thereto by dilation of said clamp operating diaphragm, means for dilating said clamp operating diaphragm with a fluid under pressure and means for thereafter dilating said sole pressing diaphragm with the same fluid pressure to press an outsole against the shoe clamped to it.

25 12. In a shoe press the combination comprising, a base member, two flexible diaphragms separated by a rigid pressure resisting plate secured to said base member forming upper and lower inflatable chambers, shoe clamping means disposed over said upper chamber and movable to clamp a shoe to its diaphragm, connections from said shoe clamping means contacting the diaphragm of said lower chamber, a valve connected with said lower chamber for inflating it with a fluid to dilate its diaphragm and thereby cause said clamping means to clamp a shoe to the diaphragm of said upper chamber and means associated with said pressure resisting plate and

30 35 automatically operated by pressure in said lower chamber to allow fluid to pass from said lower chamber to said upper chamber to dilate its diaphragm and press it against the bottom of the shoe clamped thereto.

40 45 13. In a shoe press the combination comprising, a base member, two flexible diaphragms separated by a rigid pressure resisting plate secured to said base member forming upper and lower inflatable chambers, shoe clamping means disposed over said upper chamber and movable to clamp a shoe to its diaphragm, connections from said shoe clamping means contacting the diaphragm of said lower chamber, a valve connected with said lower chamber for inflating it with a fluid to dilate its diaphragm and thereby cause

50 55 said clamping means to clamp a shoe to the diaphragm of said upper chamber, means associated with said pressure resisting plate and automatically operated by pressure in said lower chamber to allow fluid to pass from said lower chamber to said upper chamber to dilate its diaphragm and press it against the bottom of the shoe clamped thereto, and means for deflating both of said chambers.

60 65 14. In a shoe press the combination comprising, a base member, two flexible diaphragms separated by a rigid pressure resisting plate secured to said base member forming upper and lower inflatable chambers, shoe clamping means comprising separate toe and heel clamps disposed above said upper chamber and independently movable towards its diaphragm to clamp a shoe thereto, two platens pivoted to said base member for swinging movement towards and away from the diaphragm of said lower chamber, connec-

tions between said platens and said shoe clamping means, springs urging said shoe clamping means away from its diaphragm, means for inflating said lower chamber with a fluid to dilate its diaphragm and thereby cause swinging movement of said platens and movement of said shoe clamping means to clamp a shoe to the diaphragm of said upper chamber, means automatically operated by pressure in said lower chamber to allow fluid to pass into said upper chamber to dilate its diaphragm and cause it to press against the bottom of a shoe held by said clamping means and means for deflating both of said chambers.

15. In a shoe press the combination comprising, two opposed dilatable diaphragms, shoe clamping means movably disposed above one of said diaphragms, means in contact with the other of said diaphragms for moving said clamping means, and means for dilating both of said diaphragms with a fluid.

16. In a shoe press the combination comprising, two opposed dilatable diaphragms, shoe clamping means movably disposed above one of said diaphragms, means in contact with the other of said diaphragms for moving said clamping means, operator controlled valve means for dilating one of said diaphragms with a fluid and

automatic valve means for thereafter dilating the other diaphragm with a fluid.

17. In a shoe press the combination comprising, two opposed dilatable diaphragms, shoe clamping means disposed above one of said diaphragms and movable to clamp a shoe thereto, means associated with the other of said diaphragms for actuating said clamping means, and means for dilating each of said diaphragms in a definite sequence.

18. In a shoe press the combination comprising, two opposed dilatable diaphragms, shoe clamping means disposed over one of said diaphragms, means dependent upon dilation of the other of said diaphragms for actuating said clamping means, and means for dilating each of said diaphragms in a definite sequence.

19. In a shoe press the combination comprising, a frame, two opposed dilatable diaphragms secured to said frame, shoe clamping means supported by said frame for movement towards and away from one of said diaphragms, means for moving said clamping means supported by said frame for movement toward and away from the other of said diaphragms, and means for dilating each of said diaphragms with a fluid under pressure.

FRED DAWSON.
